UNITED STATES PATENT OFFICE.

JOHN H. HORN, OF PATERSON, NEW JERSEY.

SHAVING BRUSH.

Application filed April 25, 1923. Serial No. 634,471.

To all whom it may concern:

Be it known that I, JOHN H. HORN, a citizen of the United States, residing at the city of Paterson, in the county of Passaic and State of New Jersey, have invented certain new and useful Improvements in Shaving Brushes: and I do declare the following to be a full, clear, and exact description of the invention, such as will enable others skilled 10 in the art to which it appertains to make and use the same.

This invention relates to certain new and useful improvements in shaving brushes, and the primary object thereof is to provide a 15 brush of this character with improved means of a solid character for causing the brush to automatically assume a vertical position when being placed on a horizontal surface.

A further object of the invention is to provide 20 a shaving brush of simple and economical construction and wherein a single fastening is employed to rigidly connect the weighted means to the brush.

The invention still further aims to provide 25 a brush structure wherein the parts can be easily and quickly assembled and which upon assembly constitute a rigid and solid structure devoid of all moving parts.

The invention has still further and other 30 objects, which will be later set forth, and manifested in the course of the following description.

In the drawings:

Figure 1, is a side elevation of the preferred 35 form of the invention;

Figure 2 is a section on line 2—2 of Figure 1, and

Figure 3, is a side elevation partly broken 40 away and in section, of a modified form of the invention.

In proceeding in accordance with the present invention, a hard rubber socket 1 is employed having an internally threaded opening 2 at its lower end and extending through 45 the bottom face of the socket. A core or shank 3 of cylindrical form and preferably made of hard wood is threaded at its upper end into engagement with the threads of the socket. The upper end of the shank or core 50 forms a bottom for the socket 1 to receive the usual bristles 4, the latter being cemented at 5 and the bristles secured to afford what is generally termed "rubber set."

This socket 1 and core 3 constitute the 55 body portion of the shaving brush.

The weight 6 is composed of a steel jack-

eted lead member which forms a handle for the brush. The lead member is formed with a socket or bore 7 receiving the lower end of the wooden shank 3 and with an opening 8 60 receiving the fastening screw 9, the latter being projected into the wooden core 3. The weighted handle, it will be noted, is of solid immovable construction and the screw rigidly connects the wooden core or shank and 65 consequently the rubber or bristles socket member 1 to the handle.

As depicted in Figures 1 and 2 of the drawings, the seating face or supporting end 10 of the handle is of curved form, with the 70 sides of the shank of the handle curved outwardly at 11 and meeting the curved seating face, while in Figure 3 of the drawings, the seating face 10^a is of a more flat form and the sides 11^a of the shank incline on approximately straight lines and flare toward the seating face.

In both forms of the invention it will be noted that the entire handle structure is of solid form, which affords the desired self-righting action of the brush always maintaining the latter in a vertical position. Further, there are no movable parts, all of the parts employed being rigidly secured together, the flared lower portion of the handle 80 in each instance affording a weighted seating end. Of course the shank 3 could be threaded and the handle screwed thereon if desired, and in this instance the screw 8 would be dispensed with.

What is claimed is:—

1. In a self righting shaving brush, a bristle carrying socket member having an internally threaded aperture extending through the lower end thereof, a core threaded into said aperture and having its upper end forming the bottom of the socket, a relatively heavy and solid handle having an aperture conformably receiving the lower end of the core, and a screw extending 95 through the lower end of the handle and into the lower end of the core.

2. In a self-righting shaving brush, a bristle carrying socket member, a core connected to and projecting beyond said member, a relatively heavy and solid handle having a bore receiving the projecting part of the core, and a screw extending through the handle and into the core.

3. In a self righting shaving brush, an integral bristle carrying socket member having an aperture extending through the lower

end thereof, a detachable core extending within said aperture the upper face of the core forming the entire bottom of the socket while the rear portion of the core projects 5 beyond said socket, a relatively heavy and solid handle having an opening conformably receiving the projecting rear portion of

said core, and thread engaging means carried respectively by the core and handle whereby they are secured together. 10

In testimony whereof I affix my signature hereto.

JOHN H. HORN.
